UNITED STATES PATENT OFFICE.

ANNA LIND, OF BRIDGEPORT, CONNECTICUT.

SPRING-FAN.

1,328,172.

Specification of Letters Patent.

Patented Jan. 13, 1920.

Application filed September 21, 1918. Serial No. 255,115.

To all whom it may concern:

Be it known that I, ANNA LIND, a citizen of the United States, residing at Bridgeport, in the county of Fairfield and State of Connecticut, have invented new and useful Improvements in Spring-Fans, of which the following is a specification.

This invention relates to fans, and has for its object the provision of a rotary spring driven fan embodying in its construction a peculiarly constructed automatic governor which is adjustable to control the speed of rotation of the fan.

An important object is the provision of a fan of this character in which the speed controlling governor may be adjusted from the exterior of the fan casing with ease and simplicity.

A more specific object is the provision of a fan of this character in which the spring driven train of gears for operating the fan also drives a rotary member upon which are pivoted arms adapted to swing outwardly under the influence of centrifugal force for urging spring shoes in engagement with an adjustable brake band, this rotary regulator member being inclosed within a casing into which extend a plurality of adjusting screws engaging the periphery of the band for properly centering the band in respect to the rotary member.

An additional object is the provision of a rotary spring driven fan of this character which will be simple and inexpensive in construction, which will be easily controlled, efficient in use, durable in service and a general improvement in the art.

With the above and other objects and advantages in view, the invention consists in the details of construction to be hereinafter more fully described and claimed, and illustrated in the accompanying drawings in which:

Figure 1 is a front elevation of the complete device.

Fig. 2 is a front elevation thereof with the fan member and front plate of the casing removed.

Fig. 3 is an enlarged sectional view thereof.

Fig. 4 is a front elevation of the speed controlling mechanism with the cover plate thereof removed.

Fig. 5 is a cross sectional view through Fig. 4.

Fig. 6 is a detail sectional view illustrating

the construction of the double ended winding key and the remaining figures are detail views.

Fig. 7 is a front elevation thereof.

Fig. 8 is a side elevation thereof, showing a lever associated therewith.

Fig. 9 is a detail view of the ratchet stop for the spring.

Referring more particularly to the drawings the numeral 10 designates the casing of my device which is formed preferably cylindrical and within the rear portion of which is disposed a spiral spring 11 connected at one end to a post 12, which extends centrally beyond the front wall of the casing and which has its extremity squared as shown at 13 for engagement by a winding key. At its other end, the spring 11 is connected with an internally toothed ring gear 14 which is revolvably mounted within the casing 10 and which meshes with a small gear 15 which is the first of a train of gears 16 which operate to drive a gear 17 meshing with a gear 18 formed on a sleeve 19 journaled through the front wall of the casing 10 and having secured upon its outer end a fan 20 provided with any desired number of blades 21. Secured upon the inner face of the front wall of the casing 10 is a race-way 22 within which are disposed balls 23 bearing in a similar race-way 24 formed on one face of the gear 18. The usual pawl and ratchet mechanism is of course provided upon the post 12 so that the spring 11 may be wound.

In order that the speed of rotation of the ultimate gear 18 carrying the fan 20 may be controlled, I provide within the casing 10 a cylindrical housing 25 within which is disposed a rotary disk member 26 secured upon a shaft 27 extending through the housing 25 and carrying a gear 28 which in turn meshes with a gear 29 driven from the gear 17. Pivoted at diametrically opposite points on the rotary disk 26, as shown at 30, are arms 31 which have their outer ends provided with weights 32. The inner ends of the arms 31 are provided with cam surfaces 33 which engage against the free ends of spring shoes 34 secured at 35 upon the disk member 26.

Disposed within the housing 25 in concentric relation to the rotary disk 26 is a split band 36 having its ends provided with outwardly extending ears 37 which are apertured for the passage of an adjusting rod 38. The rod 38 is revoluble through one of

the ears 37 and is provided at a point spaced from its end with an enlarged portion 39 bearing against the outer side of one ear. The extremity of the rod 38 is threaded as shown at 40 for engagement within the correspondingly threaded aperture in the other ear. At its other end, the rod 38 carries a small beveled gear 41 which meshes with a beveled gear 42 formed on one end of a sleeve 43 rotatably mounted upon the stem 12 within the sleeve 19. At its outer end, the sleeve 43 is provided with teeth 44 for a purpose to be described.

In order that the band 36 may be held in proper concentric relation to the rotary disk 26, I provide a plurality of screws 45 which are threaded through the sides of the housing 25 and which bear against the outer periphery of the band 36.

In connection with my device I make use of a key formed as a cylindrical body 46 provided at one end with a square socket 47 engageable upon the squared extremity 13 of the post 12 and having its other end provided with a series of teeth 48 engageable with the teeth 44 formed on the outer end of the sleeve 46.

The operation of the device is as follows. In order to wind the spring 11, the operator places the key 46 upon the stem 12 with its squared socket 47 engaging the squared extremity 13 of the stem. By rotating the key 46 the stem 12 will be rotated and the spring will be consequently wound. The unwinding action of the spring 11 will cause the ring gear 14 to be rotated, setting in motion the gear 15 and train of gears 16 which will result in rotation of the gear 17 and consequently the gear 18, sleeve 19 and fan 20. At the same time, the gear 17 drives the gears 29 and 28 and consequently rotates the disk member 26. During the rotation of the disk member 26 the arms 31 will swing outwardly under the influence of centrifugal force, whereupon the cam surfaces 33 thereon will press the free ends of the shoe members 34 outwardly into engagement with the band 36. If the disk member 26 rotates faster than a certain predetermined rate the outward swinging movement of the arms 31 will cause the free ends of the shoe members 34 to bear against the band 36 with sufficient pressure to exert a braking action retarding the speed of the disk 26.

In order to regulate the braking action of the band 36, it is merely necessary that the operator engage the toothed end 48 of the sleeve 46 with the teeth 44 formed on the outer end of the sleeve 43 and thereby rotate the sleeve 43 and consequently the gear 42. Movement of the sleeve 43 in either direction will result in corresponding movement of the gear 41 and rod 38 which will cause the ears 37 on the band 36 to be moved

toward or from each other as the case may be. When the sleeve 43 is rotated in the direction which will result in moving the ears 37 toward each other, the braking action of the band 36 will occur at a lower speed of the disk member 26. When the ears 37 are similarly moved farther apart, the braking action of the band 36 will not occur until the disk member 26 attains a higher speed. In this manner the speed of rotation of the fan 20 may be readily controlled.

From the foregoing description and a study of the drawing it will be apparent that I have thus provided a spring driven rotary fan which will be efficient in use and in which the speed of rotation may be quickly and easily controlled entirely from the outside of the casing within which the mechanism is disposed.

While I have shown and described the preferred embodiment of the invention, it will of course be readily understood that I reserve the right to make such changes in the form, construction and arrangement of parts as will not depart from the spirit of the invention nor the scope of the subjoined claims.

Having thus described my invention I claim:

1. In a gear driven rotary fan, a rotary disk having operative connection with the drive gears, a pair of weighted arms pivoted upon said disk and provided adjacent their inner ends with cam surfaces, a pair of spring shoes secured upon said disk at one end and having their other ends engaged by said cam surfaces, a split spring band disposed in concentric relation to said disk in position for engagement by said shoes, means for centering said ring with respect to the disk, and means for varying the diameter of said band.

2. In a rotary fan, speed controlling mechanism comprising a disk driven by the driving mechanism of the fan, a pair of weighted arms pivoted upon said disk and provided adjacent their inner ends with cam surfaces, a pair of spring shoes secured at one end upon said disk and having their other ends engaging said cam surfaces, a housing surrounding said disk, a split spring band disposed within said housing in concentric relation to said disk, means for contracting or expanding said split band, and a plurality of adjusting screws extending through said housing and engaging the outer periphery of said band whereby said band may be centered with respect to said disk.

3. In a rotary fan, including a hollow driven shaft, a fan secured upon said shaft and means for rotating said shaft, a speed controlling mechanism comprising a disk having operative connection with said drive means, a pair of weighted arms pivoted upon said disk and having their inner ends pro-

vided with cam surfaces, a pair of shoe members upon said disk and engaging said cam surfaces, a split spring band disposed in concentric relation to said disk and in position to be engaged by said shoe members, ears on the ends of said split band, an adjusting rod having one end in threaded engagement with said ears, a bevel gear on

the other end of said rod, a sleeve disposed within said hollow shaft and provided at 10 its inner end with teeth meshing with said bevel gear, and means for rotating said sleeve.

In testimony whereof I affix my signature.

ANNA LIND.
